Des. 212,693
Patented Nov. 12, 1968

212,693

CATTLE NOSE TONGS

Robert E. Shell, Houston, Tex.
(P.O. Box 192, Eagle Lake, Tex. 77434)

Filed Apr. 22, 1968, Ser. No. 11,547

Term of patent 14 years

(Cl. D30—99)

The figure is a plan view of cattle nose tongs, showing my new design.

FIG. 1 is a plan view of the cattle nose tongs embodying my new design;

FIG. 2 is a plan view of the side opposite that shown in FIG. 1.

I claim:

The ornamental design for cattle nose tongs, as shown.
